Julius Hess

By his Atty: Thos. D. Mayes

UNITED STATES PATENT OFFICE.

JULIUS HESS, OF DETROIT, MICHIGAN.

REFRIGERATOR-ROOM.

SPECIFICATION forming part of Letters Patent No. 285,893, dated October 2, 1883.

Application filed May 10, 1883. (No model.)

To all whom it may concern:

Be it known that I, JULIUS HESS, of Detroit, in the county of Wayne and State of Michigan, have invented new and useful Improvements in Refrigerator-Rooms; and I do hereby declare that the following is a full, clear, and exact description thereof, reference being had to the accompanying drawings, which form a part of this specification.

10 This invention relates to improvements in the construction of refrigerating-rooms; and it consists in the method and devices herein-after described for holding and securing refrigerator boxes or tanks, with their drip-pans, in place without incumbering the space underneath and without interfering with the proper action of the air-currents, which must have free access to their cooling-surfaces.

In the drawings my method of supporting 20 such tanks is illustrated on two large refrigerating-tanks of what is called the "Davis patent." They are arranged parallel to each other and near the ceiling of a room which is destined to form a large refrigerator.

25 Figure 1 is an end view of the two tanks with their supporting devices. Fig. 2 is a side elevation. Fig. 3 is an elevation of the supporting-shoe. Fig. 4 is a plan thereof. Fig. 5 is a cross-section on line $x-x$, Fig. 3.

30 Fig. 6 is a perspective view of the iron sockets used to secure the ends of the straight T-iron bars to the ceiling. Fig. 7 is a similar view of the sockets employed to secure the ends of the curved iron bars to the ridge-piece.

35 In the accompanying drawings, which form a part of this specification, A. A are two refrigerating-tanks of known construction, and which are intended to form the refrigerating medium for producing the desired temperature 40 in the cooling-chamber B. The best position for these tanks for refrigerating purposes is to place them close to the ceiling of the room, which is a well-known practice, and I have devised the following simple way for doing 45 this without incumbering the space underneath, which is desired to be used to its full extent for the storage of the articles to be refrigerated. Each tank is supported upon its two lower ends by a series of cast-iron shoes,

C, which are so formed upon their upper faces 50 as to form sockets, into which the foot of the refrigerating-tank and the ends of the iron supports are stepped, without any necessity for the use of bolts. Upon their lower ends these shoes, which are preferably made of cast- 55 iron, are adapted to straddle the girders D, which are in turn supported upon columns E. Where two adjacent tanks meet, the girders are also supported by a single column or row 60 of columns through the medium of a cross-piece, F, which is firmly held in position upon its column by brackets a. To support the sides and bottom of the refrigerating-tank, I use ordinary T-bars, which at one end are secured in the sockets of the shoe. The shoes 65 have a central opening, G, of proper size, to receive and support a drip-pan, H, for the collection of the water of condensation.

In the particular case depicted in the drawings, where the refrigerator-tank is of the pattern known as the "Davis Refrigerating-Tank," I have adjusted the details as follows:

The shoe C (shown in Figs. 3, 4, and 5) has on top the depression or socket b, into which the foot of the tank fits, resting upon 75 the bridge c.

d and e are sockets for the supporting-bars I and J.

G is an opening through the shoe for the admission and support of the drip-pan H. 80 f' is the bottom of the shoe, which, in conjunction with the lugs g, forms a saddle for its proper support upon the girder D.

h are shields intended to throw the drip from the sides of the tank which happens to 85 collect upon the top of the shoe into the drip-pan.

i are little notches intended to properly guide the drip onto the shields h. The supporting-bars I are at their upper ends secured 90 to the ceiling of the room by means of sockets K, (shown in Fig. 6,) and the curved ribs J, which support the bottom, are fitted with sockets L, which are secured to a ridge-piece, M, as shown in Figs. 1 and 7.

95 What I claim as my invention is—

1. The method herein described for constructing refrigerating-rooms, consisting in sup-

porting the tanks upon columns arranged in single rows and topped with one or two parallel girders, which support a series of shoes, into which the foot of the refrigerating-tanks and the foot of all supporting-bars are stepped, substantially as and for the purpose described.

5. 2. A supporting-shoe containing sockets for the support of the refrigerating-tank and the

supporting T-iron, in combination with an interior opening for the support of the drip-pan, substantially as specified.

JULIUS HESS.
